HIS ATTORNEY

UNITED STATES PATENT OFFICE.

EDWIN E. BARNEY, OF ILION, NEW YORK, ASSIGNOR TO REMINGTON TYPEWRITER COMPANY, OF ILION, NEW YORK, A CORPORATION OF NEW YORK.

TYPE-WRITING MACHINE.

1,284,214.

Specification of Letters Patent. Patented Nov. 12, 1918.

Application filed September 20, 1916. Serial No. 121,284.

To all whom it may concern:

Be it known that I, EDWIN E. BARNEY, citizen of the United States, and resident of Ilion, in the county of Herkimer and State 5 of New York, have invented certain new and useful Improvements in Type-Writing Machines, of which the following is a specification.

My present invention relates to locking devices for screws or bolts, and its general object is to provide improved devices of the character specified.

My novel screw locking devices have been designed more particularly for use in type-writing machines in connection with the adjustable screws that regulate the tension of the restoring springs for the key levers, and the special object of the invention is to provide new and improved devices for setting or locking said screws while affording independent adjustments thereof in order to vary and regulate the tension or force of the springs with which they coöperate.

To the above and other ends my present invention consists in the features of construction, combinations of devices and arrangements of parts hereinafter described and particularly pointed out in the claims.

In the accompanying drawings,

Figure 1 is a fragmentary front to rear vertical sectional view of the lower portion of a front strike Remington typewriting machine embodying the preferred form of my invention.

Fig. 2 is a transverse sectional view taken on planes indicated by the broken dotted line $\alpha\alpha$ in Fig. 1.

Fig. 3 is a fragmentary plan view of the supporting bar.

Fig. 4 is an enlarged fragmentary sectional view showing my improved devices in connection with one of the key levers.

Fig. 5 is a bottom plan view of a part hereinafter termed a stud.

As appears from Fig. 1, the base 1 of the main frame of the Remington typewriting machine has arranged within it a set of key operated elements or key levers 2 which are fulcrumed at 3 in rear of the base, the key levers each being provided with a key cap or button 4 and being connected as usual by devices comprising links 5 with type bars of ordinary construction not herein disclosed. Each key lever as heretofore is provided 55 with an individual restoring spring 6 which

assists to restore it and the parts connected to it to normal position after operation. In the present instance the restoring spring 6, Figs. 1, 2 and 4, are coiled compression springs vertically arranged below the key 60 levers, the upper end of each spring being held in position by a lug or projection 2^a on the key lever with which the spring is associated. The upper portion of the spring fits loosely around the lug which serves as a 65 guide for it. The lower end portion of each spring fits loosely over and is guided by the upstanding shank 7 of a slid able member or stud 8 which further comprises a head 9, the shape of which best appears in Figs. 4 70 and 5. This head is generally round but has two diametrically opposite triangular lugs or extensions 9^a projecting from it. It will be understood that there is provided a set of these studs associated with each spring 75 6. The studs 8 are arranged in line with each other across the machine and are slidably mounted in vertical guide holes 10 formed transversely in a supporting bar or part 11, a partial plan of which is shown in 80 Fig. 3. This bar is arranged in the lower portion of the base 1, extending transversely of the base, and having its ends suitably secured as by screws 11^a to the sides of the base so that the bar may be readily detached and 85 replaced. The holes 10 are formed by first drilling the bar, providing round holes, then tapping these holes to provide threads for the adjusting screws hereinafter described, and finally broaching the tapped holes or 90 cutting them with a broaching tool, so as to shape them properly to receive the heads of the studs or members 8, the fit of the heads being such that the studs may slide readily up and down in the holes but are 95 prevented from turning by the engagement of the extensions 9^a with the corresponding portions 10^a of the holes 10. Across the head of each stud diametrically 100 opposite from the projections 9^a is formed a small concave groove or slot 12 which is engaged by a projection or tongue 13 milled on the inner end of an adjusting screw or bolt 14 which is provided at its opposite or lower end with a nick or driving slot 15. This 105 screw is entered in the associate tapped and broached hole 10 at the bottom and advanced upward by screwing it in until it properly coöperates with the groove or nick 12 in the associate stud 8. It will be apparent that the 110

compression spring 6 re-acts from the key lever 2, which provides an unvarying normal position for its upper end, and presses downward through the hole in which it is 5 partly seated or housed on the head of the stud 8 so that there is a constant downward pressure on the stud, tending to lower it in its hole 10. This action of the stud is transmitted through the projection 13 to the screw 10 14 with the resulting tendency to bind the threads of the screw against the threads in the hole. In other words, the interposed member or spring pressed stud 8 exerts a locking or holding effect on the screw which 15 tends to maintain the screw set in adjusted positions. The construction is such that a ready adjustment of the tension of the spring 6 is afforded by screwing the screw 14 in or out. In either case it will be plain that when 20 the screw is first turned the projection 13 will coöperate with the groove 12 to exert a camming action on the stud or member 8, the result being that the stud will be forced upward as the projection 13 turns trans- 25 versely of the groove 12. The turning move- ment of the crew 14 will be continued until a half turn has been completed, whereupon the projection 13 will reëngage with the groove 12, but as a result of the turning 30 movement of the screw the stud will have been raised a distance corresponding to half the pitch of the screw thread and the spring 6 will have been correspondingly com- 35 pressed. Similarly by unscrewing the screw 14 the tension of the spring may be correspondingly lessened or relaxed. The construction provides for varying the tension by compressing the spring or relaxing it by moving the slidale stud or abutment 8 step- 40 by-step to predetermined extents, these ex- tents being equal and corresponding to half the pitch of the screw; that is, the screw or rotary tension adjusting member must be turned in a half turn before it can be set by 45 coöperation with the groove 12 or turned out a half turn to arrive at the same result. Ob- 50viously the only way in which the normal tension or tendency of the spring 6 to ex- pand can be varied is by turning the rotary adjusting member or screw 14 either in or out, and as it is clear that any accidental turning of the screw will be resisted by the sloping or cam sides of the notch or groove 55 12 acting against the projection or tongue 13 with the full expansive force of the spring 6 behind it, the construction provides an effective locking or holding means to prevent accidental rotation of the screw 14 and con- sequent alteration of the force of the spring 6. While the screw may turn slightly at 60 times as the result, for example, of jarrings incident to the operation of the machine, it is clear that the slipping sides of the groove 12, acting as cams, will exert a corrective 65 effect and restore the screw to the position

from which it was jarred or otherwise accidentally moved or turned.

Various changes may be made without departing from my invention and it may be applied to machines other than typewriting 70 machines and in which the spring coöperates with a part or device not a key lever.

What I claim as new and desire to secure by Letters Patent, is:

1. The combination of a compression 75 spring, one end of which has an unvarying normal position, a screw, and a member interposed between the other end of said spring and said screw, said member transmitting the effect of the screw as it is turned 80 to the spring, said member being provided with devices which assist to prevent its own rotation and being also provided with devices which assist to prevent accidental rotation of said screw.

2. The combination of a compression spring, a rotary tension adjusting member, and a slidale member interposed between said adjusting member and said spring, one of said members having a projection or 90 tongue engaging a groove or depression in the other member.

3. The combination of a compression spring held at one end, a member provided with a cam coöperative with the other end 95 of said spring, and a screw for controlling the tension of said spring, said screw having a part coöperative with said cam.

4. The combination of a coiled spring and tension adjusting devices therefor which 100 permit predetermined extents of variation in the compressive force of said spring, said means comprising a slidale grooved member and a screw that engages in the groove in said member.

5. The combination of a coiled spring, a member comprising a grooved head and a shank, a spring fitting over said shank and engaging with said head, and a rotary mem- 110 ber coöperative with the groove in said head.

6. The combination of a coiled spring, a member comprising a grooved head and a shank, a spring fitting over said shank and engaging with said head, and a threaded 115 member having a projection engaging in said groove.

7. The combination of a coiled compression spring, a part provided with a hole in which said spring is partly housed, a guide 120 member for said spring slidale in said hole, and a tension adjusting member rotatable in said hole and thereby controlling the movements of said guide member, said guide member being provided with devices which assist 125 to prevent its own rotation in said hole and also being provided with devices which assist to prevent accidental rotation of said tension adjusting member.

8. The combination of a coiled compres- 130

- 5 sion spring, a part provided with a hole in which said spring is partly housed, a guide member for said spring slidable in said hole, and a tension adjusting member rotatable in said hole and thereby controlling the movements of said guide member, one of said members being provided with a transverse groove and the other with a projection engaging in said groove.
- 10 9. The combination of a coiled spring, a part provided with a threaded hole having broached sides, said spring being partly housed in said hole, a screw threaded into the opposite end of said hole from said spring, and a member slid able in said hole in one direction by said screw and in the opposite direction by said spring, said member engaging with the broached sides of said hole which prevent its rotation.
- 15 10. The combination of a coiled spring, a part provided with a threaded hole having broached sides, said spring entering said hole, a screw threaded into said hole, and a member slid able in said hole and against which said spring abuts, said member engaging with the broached sides of said hole which prevent its rotation and being provided with a cam coöperative with said screw.
- 20 11. In a typewriting machine, the combination of a key lever, a slid able member, a coiled spring confined between said key lever and said slid able member, and means for affording step by step adjustments of said member through equal predetermined extents of movement.
- 25 12. In a typewriting machine, the combination of a set of key levers, a set of coiled restoring springs, a cross bar provided with
- 30 a series of holes, a set of members slid able in said holes and coöperative with said springs, and a set of screws threaded into said holes and coöperative with said members, said members holding said screws against accidental displacement.
- 35 13. The combination of a bar provided with holes, a plurality of compression springs partly housed in said holes, key controlled members with which said springs co-operate, rotary tension adjusting members, and slid able parts interposed between said adjusting members and said springs, said slid able parts holding said tension adjusting members against accidental displacement.
- 40 14. The combination of a bar provided with a series of holes arranged in a straight line, compression springs partly seated in said holes, rotary tension adjusting members in said holes, and slid able members in the holes between said rotary members and said springs, said slid able members coöperating with said rotary members to prevent displacement thereof.
- 45 15. The combination of a bar provided with a set of tapped and broached holes, screws threaded into said holes, slid able studs in said holes transversely grooved to coöperate with said screws, coiled springs partly housed in said holes and engaging with said studs, and a series of parts on which said springs act.

Signed at Ilion, in the county of Herkimer and State of New York, this 18th day of September, A. D 1916.

EDWIN E. BARNEY.
